UNITED STATES PATENT OFFICE.

WALTER S. ADAMS, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

LOCKING DEVICE FOR CAR-SEATS.

1,121,443.

Specification of Letters Patent. Patented Dec. 15, 1914.

Application filed May 9, 1911. Serial No. 626,011.

To all whom it may concern:

Be it known that I, WALTER S. ADAMS, a citizen of the United States, residing in Philadelphia, Pennsylvania, have invented 5 certain Improvements in Locking Devices for Car-Seats, of which the following is a specification.

The object of my invention is to construct 10 a car seat having a reversible back so that the cushion section cannot be removed from the frame unless the back is in the mid-position. This object I attain in the following manner, reference being had to the accompanying drawings, in which:—

15 Figure 1, is a transverse sectional view through the car seat, illustrating the end of the cushion section; the back, in this instance, being in the mid-position; Fig. 2, is a view showing the back thrown over to one 20 side; Fig. 3, is an inverted plan view of the cushion section; Fig. 4, is a view of a modification of the construction illustrated in Fig. 1; and Figs. 5 and 6, are views of modifications of my invention.

25 A is the frame of the car seat having a surface α upon which rests the carrying frame B. This frame is curved on its lower side so as to slide from the center position, Fig. 1, to either of its extreme positions, one 30 of which is shown in Fig. 2. In the present instance projecting from the frame B are pins b , b , which enter the frame of the seat cushion D. The supporting frame B has a vertical slot b' formed by flanges projecting from one side of the frame.

35 E is the back of the seat, having arms C pivoted to the shaft F which extends from one end of the seat to the other in the present instance. On an extension C' of the 40 arm C is a pin c which projects into the slot in the frame B, so that as the back is shifted from one side of the seat to the other the seat cushion section D will be moved in the opposite direction to make the seat comfortable for the occupant. This is a common construction of car seats of this type.

To the underside of the seat cushion frame I secure plates I, I by means of screws or bolts i . These plates are bent so as to extend below the line of the shaft F and are of such length as to allow the seat cushion to move to either of its extreme positions without interfering with the shaft F. The two

plates I, I are also spaced apart at the center a sufficient distance to allow for the passage of the shaft between the plates when the back section is in the position shown in Fig. 1. When it is necessary to remove the seat section, the back section is shifted to the central position, Fig. 1, and as the space between the plates is in line with the shaft F, the seat section can be raised off of its supports and removed, but when the back is moved to one side or the other of the seat structure, the plates I, I prevent the removal of the seat from its supports, as the plates underlap the shaft F. These plates also prevent the tilting of the seat section. 55 60 65

While I have shown the plates I, I secured to each end of the cushion section, as 70 illustrated in Fig. 3, a single pair of plates may be mounted at or about the center of the seat section to accomplish the same purpose.

In Fig. 4, I have illustrated a modification 75 in which the slot i' is formed in a plate I^2 ; the arms i^2 of the plate extending toward each other and being spaced a sufficient distance apart to allow for the passage of the shaft.

In Fig. 5, I have illustrated a modification, in which two arms I' are secured to the seat frame and on the underside of the seat cushion section is a pin d . The arms are spaced a sufficient distance apart to allow for the withdrawal of the pin when the seat cushion section is in the mid-position. 80 85

In Fig. 6, I have shown arms I^3 secured to the shaft F, so that when the back and seat sections are in the central position the pin d' on the seat alines with the space between the arms, and when the parts are moved from the central position the engagement is more quickly effected. 90

The main object of the invention is to 95 provide means for preventing the accidental removal or tilting of the seat cushion section when the seat is in position to be occupied by passengers. The plates may be shaped so as to form stops to limit the outward 100 movement of the cushion section when in either of its extreme positions.

The invention can be applied to any form of car seat and any of the ordinary means for simultaneously shifting the cushion section and the back may be employed. 105

I claim:—

1. The combination in a car seat structure, of a frame; a seat support arranged to slide on the frame; a seat section movably mounted on the seat support; a transverse shaft located under the seat section and having its bearings in the frame; an arm on said shaft engaging the seat support and another arm on the shaft to which the back is attached; with a guard having a slot therein and mounted on the under side of the seat section, the guard being shaped to allow for the free movement of the seat over the shaft, the slot in the guard being so located that when the seat is in the mid position it can be bodily removed from its support.
2. The combination in a car seat structure, of a seat section and a transverse shaft located under the seat section; a slotted guard on one of said parts and an element

on the other part with which the guard engages; a frame; a seat support arranged to slide on the frame and arranged to carry the seat section; an arm on the shaft to which the back of the seat is secured; and means for causing the seat support to slide as the back is shifted from one side to the other, the parts being so arranged that when the back is in the central position the slot of the guard on one part will be in line with the element on the other part so that the seat section can be bodily removed from the seat structure.

In testimony whereof, I have signed my name to this specification, in the presence of two subscribing witnesses.

WALTER S. ADAMS.
